UNITED STATES PATENT OFFICE.

FRANK S. BARKS, OF ST. LOUIS, MISSOURI.

METAL BEAM.

1,217,685.

Specification of Letters Patent. Patented Feb. 27, 1917.

Application filed May 6, 1916. Serial No. 95,798.

To all whom it may concern:

Be it known that I, FRANK S. BARKS, a citizen of the United States, residing at St. Louis, Missouri, have invented a certain new 5 and useful Improvement in Metal Beams, of which the following is a full, clear, and exact description, such as will enable others skilled in the art to which it appertains to make and use the same, reference being had 10 to the accompanying drawings, forming part of this specification.

My invention relates to a rolled metal beam, the principal object of my invention being to provide a beam which can be easily 15 manufactured by the rolling process and which is shaped and flanged so as to render it particularly applicable for use as a draft sill or arm and for supporting the usual draft rigging which is associated with car 20 underframes.

A further object of my invention is to provide a rolled metal beam with flanges, so arranged as to readily accommodate under-frame and draft rigging parts which are 25 usually associated with the draft sills of cars, and further to provide a one-piece beam, parts of which are relatively disposed so as to coöperate and unite with under-frame parts, which latter occupy fixed positions 30 under the M. C. B. standards.

With the foregoing and other objects in view, my invention consists in certain novel features of construction and arrangement of parts, hereinafter more fully described, 35 claimed and illustrated in the accompanying drawings, in which—

Figure 1 is a perspective view of a portion of a beam of my improved construction, the body of said beam being shown in 40 section.

Figs. 2, 3, 4 and 5 are cross sectional views of modified forms of the beam.

Fig. 6 is a cross sectional view of a modified form of the beam, wherein certain of 45 the flanges are separately formed and secured to the body of the beam by rivets or like fastening devices.

Referring by numerals to the form of beam illustrated in Fig. 1, 10 designates the 50 web or body of the beam, the same being of any desired width, length and thickness, said web being bent as designated by 11 at a point near its center so that approximately half of said web or the portion designated by 10^a is offset with respect to and occupies

a plane to one side of and parallel with the plane occupied by, the opposite portion 10^b.

Formed integral with the edge of web portion 10^a is an outwardly projecting base flange 12 and formed integral with said 60 web portion near the central bend 11 is an outwardly projecting flange 13, the same extending in the same direction as the flange 12 and being arranged parallel therewith.

Formed integral with and projecting outwardly from the edge of the portion 10^b is a horizontally disposed flange 14, the same projecting in a direction opposite to that in which the flanges 12 and 13 project and formed integral with said portion 10^b near 70 the central bend 11 is a flange 15, the same projecting outwardly in the same direction with flange 14 and being arranged parallel therewith.

By this construction, it will be seen that I 75 have provided a beam which is composed of a web having off-set portions, each of which latter is provided with a pair of flanges, the same projecting in opposite directions and being disposed approximately at right angles 80 to the planes occupied by the off-set portions of the web.

This construction produces in effect a pair of channels, the webs of which are arranged parallel with each other and the adjacent 85 corners being connected by an integral web portion.

A beam so constructed can be rolled in any desired and convenient length and after being properly formed, the beam can be cut 90 into sections suitable for use as draft sills. When a pair of the beams are utilized as draft sills, the beams are arranged with the webs 10 vertically disposed, with the flanges 14 and 15 of the two beams projecting toward each other and toward the center line 95 of the car, and with the flanges 12 and 13 of said beams projecting outwardly away from the center line of the car. When so arranged, the upper portions 10^b of the webs 100 lie immediately against the inner faces of the center sills of the car underframe, the space between which center sills is fixed by M. C. B. practice, and the distance between the lower portions 10^a of the vertical webs 105 meets the M. C. B. requirements for draft rigging space.

The form of beam illustrated in Fig. 2 comprises a web having off-set portions 16 and 17, said portion 16 being provided with 110

a pair of integral outwardly projecting flanges 18 and the portion 17 being provided at its outer edge with a flange 19 which is oppositely disposed with respect to the 5 flanges 18.

In the form of beam illustrated in Fig. 3, the web is composed of a pair of off-set portions 20 and 21, the bend or shoulder 22 between said portions being very abrupt and 10 occupying a plane substantially at right angles to the planes occupied by the portions 20 and 21. In this form, the portion 20 is provided with outwardly projecting parallel flanges 23, the inner one of which occupies 15 substantially the same plane with the bend or shoulder 22 between the portions 20 and 21.

Portion 21 is provided at its outer edge with a flange 24 which is oppositely disposed 20 with respect to the flanges 23.

In the form of beam illustrated in Fig. 4 which is very similar in structure to the form illustrated in Fig. 3, the web portion 21 is provided with an integral outwardly 25 projecting flange 25, the same occupying a plane parallel with and projecting in the same direction as the flange 24.

In the modified form illustrated in Fig. 5, the web 26 of the beam is preferably straight 30 or without the central bend and projecting outwardly from the lower half of said web is a pair of parallel flanges 27 and projecting in the opposite direction from the upper half of said web is a pair of parallel flanges 28.

In the modified form illustrated in Fig. 6, the web 29 of the beam is formed from a heavy sheet or plate of metal, bent near its 35 center as designated by 30 to form off-set portions and the edge of one portion is bent 40 so as to provide a flange 31 which projects outwardly substantially at right angles to said web and the opposite edge of the web being bent to form a flange 32 which projects outwardly from the web and in a direction 45 opposite to that in which the flange 31 projects.

Rigidly fixed in any suitable manner to the off-set portions of the web and at points near the central bend 30 are angles 33, the outwardly projecting legs or flanges of which 50 occupy planes substantially parallel with the planes occupied by the flanges 31 and 32.

In some instances it may be found desirable to reinforce one or both edges of the web of the beam with bulbs as illustrated by 55 dotted lines in Fig. 5.

Beams of my improved construction can be readily manufactured, can be tooled and machined much easier and with less expense 60 than castings and by virtue of their peculiar shape and the arrangement of their flanges, said beams are particularly desirable for use as draft arms for railway car underframes.

I claim:

1. As a new article of manufacture, a commercially rolled metal draft sill having the same cross sectional area throughout its length and comprising a web which is bent near its transverse center to form offset portions which occupy substantially parallel planes, a marginal flange projecting from the edge of one of the offset portions of said web, and a pair of flanges projecting from the other offset portion of said web, said 75 pair of flanges being arranged on the opposite side of the web from the first mentioned flange with one of the flanges of said pair adjacent to the margin of the web and the other flange adjacent to the central portion 80 of the web, all of which flanges occupy planes substantially at right angles to the planes occupied by the offset portions of the web.

2. As a new article of manufacture, a commercially rolled metal draft sill having the same cross sectional area throughout its length and comprising a web which is bent near its transverse center to form offset portions which occupy substantially parallel 85 planes, a pair of flanges projecting from each offset portion of the web, one flange of each pair being disposed adjacent to the marginal edge of the web and the other flanges being disposed adjacent to the offset portion of the 90 web, the pairs of flanges projecting in opposite directions away from the web and all of which flanges occupy planes substantially 95 at right angles to the planes occupied by the offset portions of the web.

In testimony whereof I hereunto affix my signature this 14th day of April, 1916.

FRANK S. BARKS.
